US00D963731S

(12) **United States Design Patent** (10) Patent No.: **US D963,731 S**
(45) Date of Patent: **** Sep. 13, 2022**

(54) **DIGITAL CAMERA**

(71) Applicant: **CANON KABUSHIKI KAISHA**,
Tokyo (JP)

(72) Inventors: **Kazuaki Yamana**, Kawasaki (JP);
Masayasu Shigematsu, Tokyo (JP);
Jun Kamiya, Kawasaki (JP)

(73) Assignee: **Canon Kabushiki Kaisha**, Tokyo (JP)

(**) Term: **15 Years**

(21) Appl. No.: **29/744,786**

(22) Filed: **Jul. 31, 2020**

Related U.S. Application Data

(62) Division of application No. 35/507,100, filed on Nov. 14, 2018 (U.S. filing date under 35 U.S.C. 384), and having an international filing date of Nov. 14, 2018, now abandoned.

(57) **CLAIM**

The ornamental design for a digital camera, as shown and described.

DESCRIPTION

FIG. 1 is a Front view of a digital camera showing our new design;

FIG. 2 is a Back view thereof;

FIG. 3 is a Top view thereof;

FIG. 4 is a Bottom view thereof;

FIG. 5 is a Left view thereof;

FIG. 6 is a Right view thereof;

FIG. 7 is a Front Perspective view thereof; and,

FIG. 8 is a Front Perspective view thereof from a different angle than FIG. 7.

The broken lines show portions of the digital camera that form no part of the claimed design.

1 Claim, 8 Drawing Sheets
